UNITED STATES PATENT OFFICE

EDWARD KARFIOL, OF NEW YORK, N. Y.

DESIGN FOR A DOILY

Application filed February 17, 1933. Serial No. 47,243. Term of patent 14 years.

To all whom it may concern:

Be it known that I, EDWARD KARFIOL, a citizen of the United States, residing in New York, in the county of New York and State of New York, have invented a new, original, and ornamental Design for a Doily, of which the following is a specification, references being made to the accompanying drawing, forming part thereof, in which:

Fig. 1 represents a face view of a doily showing my new design for a background.

Fig. 2 shows an enlarged view of a portion of the members or bars which constitute my invention.

The full lines of the drawing shows one-quarter of the design in detail, the other three-quarter sections indicated in dotted lines except the scalloped border which is shown in full lines being repetitions of the

detailed illustration arranged in proper relation thereto.

The background element which constitutes the dominant feature of the design consists of a plurality of substantially equidistant spaced members or bars which are connected by a series of similar bars approximately at a right angle and substantially equidistant apart, these bars are spaced so as to break joints and their arrangement with regard to each other constitutes a bond formation or network of small quadrangle shaped openings or tills. The bars merge with the subject matter or motif of the doily as well as with the border.

I claim:

The ornamental design for a doily as shown and described.

EDWARD KARFIOL.
